UNITED STATES PATENT OFFICE.

JOHN E. JOHNSON, OF LAFAYETTE, ILLINOIS.

DRAFT-EQUALIZER.

SPECIFICATION forming part of Letters Patent No. 357,832, dated February 15, 1887.

Application filed December 3, 1886. Serial No. 220,571. (No model.)

To all whom it may concern:

Be it known that I, JOHN E. JOHNSON, a citizen of the United States, residing at Lafayette, in the county of Stark and State of Illinois, have invented certain new and useful Improvements in Draft-Equalizers, of which the following is a specification.

This invention relates to draft-equalizers; and it consists in constructions and combinations hereinafter described and claimed.

In the accompanying drawings, which illustrate my invention, Figure 1 is a top plan; Fig. 2, a top plan with the double-trees, single-trees, and equalizing-chain removed; Fig. 3, a front elevation of the draft-bars and bracket B, and section of the tongue; Fig. 4, a detail, a plan of the slotted bracket.

Referring to the drawings by letters, the same letters indicate the same part in the different figures.

A represents the tongue of a harvester or grain-binder, which is supposed to be located with reference to the machine in such manner that there will be, when in use, a side draft 25 tending to pull the tongue to the left hand, as is common in this class of machines.

B is a bracket formed of bars b b, bolted to the side of the tongue at one end to project in a direction from the tongue opposite to 30 which the side draft of the machine draws the tongue. The outer ends of the bars b are united by a bar, b', in which is a slot, b'', which is parallel or about parallel with the tongue.

C is a bracket secured to and projecting laterally from the side of the tongue opposite to the bracket B. The bracket C is formed of bars c c, with series of holes c', through which bolts c'' pass to secure them to the tongue in such manner as to permit of adjusting the 40 bracket to increase or diminish the distance of the pulley c'' from the tongue, which pulley is journaled on the outer end of the bracket C.

D is a bar bolted to the tongue and to one arm of the bracket B, and has a series of holes, 45 d. The pulleys d' d'' are journaled to the bar D and stayed by straps d'''. The pulleys d' d'' are adjustable lengthwise of the bar D by means of the holes d in an evident manner.

E is the equalizing-bar forming part of an ordinary four-horse double-tree, except that 50 one of its ends, E', is extended and rests so as

to slide on the tongue A. At about one-third of the length of the bar E from its outer end it is fixed to a bolt, e, which passes through and is free to slide lengthwise of the slot b''. 55 The bolt e turns in the slot b'', and permits the bar E to swing, as shown by dotted lines at Fig. 2, but at the same time fits snugly to the sides of the slot and prevents endwise movement of said bar E. 60

The double-trees G G' are hinged or journaled to the equalizing-bar E in an ordinary manner, briefly described, as follows: The bar G is hinged at its mid-length to the outer end of the bar E by a bolt, g, and the bar G' is hinged 65 to the bar E by a bolt, g', at the mid-length of the bar G', and at a point in the bar E same distance from the bolt e as is the bolt g, but toward the opposite end of the bar E from the bolt g. A block, g'', holds the bar G' above 70 the bar G. The double-tree G has a single-tree, g''', at each of its ends, and the double-tree G' has a single-tree, g''', at each of its ends.

H is the draft-chain or equalizing-chain, which, near its mid-length, passes around the 75 pulley c''. One end, h, of the chain H is secured to a clevis, h', which is hinged or journaled on the bolt g, and its other end, h'', is secured to a clevis, h'', which is journaled on the bolt g'. The end h of the draft-chain is preferably passed to one side of the pulley d', by which it is deflected toward the left-hand side of the tongue, and the end h'' is deflected in a similar manner by the pulley d'', for purposes hereinafter described. The chain H is of such 80 length as to hold the bolt e at all times free of the forward end of the slot b''; hence the force exerted by the draft-animals in drawing the machine acts nearly entirely on the pulley c'', and thus exerts a lateral force or side draft on the 85 tongue in a contrary direction to the side draft of the machine, and which lateral force may be adjusted to equal the side draft of the machine by extending the bracket C, as hereinbefore described. 90

Where the side draft of the machine is very great, the chain H may be deflected by the pulleys d' d'' to increase the force of the side draft of my improvement in an evident manner, and by adjusting the pulleys d' d'', as herein described, this increased force may be adjusted in quantity as required. 95 100

The chain H moves freely on the pulley c''' to permit either end of the bar E to advance or recede as said bar oscillates on its fulcrum e, and the bolt e is free to move in the slot b'' any distance forward or rearward required by ordinary contraction or extension of the chain H without the bolt e coming in contact with either end of the slot b''. The extended end E' of the equalizing-bar E, resting on the tongue, acts as a support for the bolt e in sustaining the four-horse double-tree.

It will be evident that my improvement may be used in any machine with side draft, and that three-horse or two-horse double-trees may 15 be used with my equalizing-bar E, chain H, and side pulley, c'''; hence I do not limit my claims to the use of a four-horse double-tree; but—

What I claim as new, and desire to secure 20 by Letters Patent, is—

1. In a draft-equalizer, in combination with a tongue, substantially as described, a bracket, B, projecting from one side of the tongue and having a slot, b'', in its outer end, an equalizer-bar, fulcrumed in said slot b'', and provided with suitable draft-bars, a bracket located on the opposite side of the tongue from the bracket B and carrying a pulley, c''', and a chain, H, passed around the pulley c''' and 25 connected with the equalizing-bar, for the purpose specified.

2. In a draft-equalizer, in combination with a tongue, a side bracket with slot b'' in its outer end, which is parallel with the tongue, 30 and an equalizing-bar fulcrumed in said slot, whereby it may have a reciprocating movement lengthwise of the tongue, substantially as and for the purpose specified.

3. In a draft-equalizer, in combination with

a tongue, a side bracket with slot b'' parallel 40 with the tongue in its outer end, and an equalizer-bar fulcrumed in said slot, whereby it may have a reciprocating movement lengthwise of the tongue, provided with double-trees, and extended at one end, E', to rest on 45 the tongue, substantially as and for the purpose specified.

4. In a draft-equalizer, in combination with a tongue, A, a bracket, C, with slot b'' in its outer end, bar E, and bolt e, carrying suitable 50 draft-bars, bracket C, carrying a pulley, c''', and chain H, substantially as and for the purpose specified.

5. In a draft-equalizer, in combination with a tongue, A, a bracket, C, with slot b'' in its 55 outer end, bar E, and bolt e, carrying suitable draft-bars, and an adjustable and extensible bracket, C, carrying a pulley, c''', substantially as and for the purpose specified.

6. In a draft-equalizer, in combination with a tongue, a bracket, C, with slot b'' in its outer end, bar E, and bolt e, carrying suitable draft-bars, chain H, bar D, carrying pulleys d' d'', and bracket C, carrying pulley c''', substantially as and for the purpose specified. 60

7. In a draft-equalizer, in combination with a tongue, a bracket, C, with slot b'' in its outer end, bar E, and bolt e, carrying suitable draft-bars, chain H, bar D, carrying adjustable pulleys d' d'', and bracket C, carrying pulley c''', 70 substantially as and for the purpose specified.

In testimony whereof I affix my signature in presence of two witnesses.

JOHN E. JOHNSON.
